UNITED STATES PATENT OFFICE.

RUFUS R. GILLESPIE, OF FORT WAYNE, INDIANA.

GARMENT-ADJUSTER.

SPECIFICATION forming part of Letters Patent No. 371,056, dated October 4, 1887.

Application filed April 27, 1887. Serial No. 236,384. (No model.)

To all whom it may concern:

Be it known that I, RUFUS R. GILLESPIE, a citizen of the United States, residing at Fort Wayne, in the county of Allen and State of Indiana, have invented certain new and useful Improvements in a Combined Hat-Rack and Garment-Adjuster, of which the following is a specification, reference being had therein to the accompanying drawings.

10 The object of this invention is to provide a holder for a cloak or coat that will aid the wearer in putting the said garment on; and to this end the invention consists of a suitable holder with a catch or other means of maintaining it in any desired position, and means for elevating the holder when released from the catch.

15 In the drawings, Figure 1 is a front elevation of the device as combined with a rack for hats or garments. Fig. 2 is a vertical section showing the catch device in side elevation. Fig. 3 is a side elevation of the device. Fig. 4 is a detail view of a modification of the garment holding clamps.

20 25 In the drawings is shown a board, A, surrounded by a lateral strip, B, carrying pins or hooks C for hats or garments. By means of suitable fastening devices the board A may be secured to a wall or other place that may 30 be desirable.

25 By means of a pivot-rod, D, extending through ears E on the board A, are supported the lower ends of arms F, diverging upward and outward. These arms are connected at 35 any intermediate point by a bar, G, which may be fixed to the said arms immovably. The arms F are sustained, normally, in an elevated position by springs K, extending from the bar G, or from the arms, or from both, to 40 the board A.

30 Pivoted to the board is a catch-bar, L, having a series of notches or teeth, M, on one edge, and adapted to engage one edge of the bar G, which is beveled for the purpose, the 45 said catch-bar L serving to retain the arms F against the action of the springs when the said arms are drawn downward, it being evident that the bar G, resting in any one of the

notches M, will hold the arms F in the lowered position. On the end of each arm is hinged a 50 block, N, which block is provided with a projection, O, adapted to a recess, P, in the end of the arm; also, on the end of each arm is a swinging yoke, R, carrying a block, S, arranged to bear against the block N, when depressed, and force it against the arm. The block N, with the means for forcing it against the end of the arm, forms a clamp for holding 55 the garment to be put on.

Instead of the block S, the yoke R may be 60 provided with a thumb or set screw for the same purpose.

The upper end or collar of the garment is clamped to the ends of the arms F, so that the inside of the garment will be outward. The 65 arms F are then depressed and held by the catch-bar. The wearer then inserts his arms in the sleeves, and by a downward pressure carries the bar G from engagement with the notches M, permitting the catch-bar L to fall 70 and thereby release the arms. The springs will then carry the coat upward and onto the wearer. The clamps may then be released and the garment be disengaged from the device.

75 I do not limit myself to the exact construction and arrangement of parts shown, as the same may be varied without departing from the spirit of my invention, the essential features of the same being to hold the garment 80 stationary while it is being adjusted to the person, and draw it upward when released, thereby assisting the putting on of the garment very materially.

Having described my invention, what I claim 85 is—

1. A device for facilitating the putting on of garments, consisting of pivoted arms, each carrying clamps for holding the garments, and means, substantially as described, for automatically elevating the said arms when released, substantially as herein set forth.

2. In a device for facilitating the putting on of garments, the combination of the pivoted arms, each carrying clamps for holding the 95 garments, a cross-bar connecting the said arms,

means, substantially as described, for automatically elevating the arms when released, and a catch-bar engaging with the said cross-bar, for holding the said arms in a lowered position, substantially as specified.

3. The combination of the pivoted arms, means, substantially as described, for elevating the same when released, a cross-bar connecting the said arms, and a pivoted catch-bar engaging with the said cross-bar, for hold-

ing the arms in a lowered position, substantially as described.

In testimony whereof I affix my signature in presence of two witnesses.

RUFUS R. ^{his} X GILLESPIE.
mark.
